United States Patent

Des. 236,493
Patented Aug. 26, 1975

236,493

ELECTRIC BATTERY

Gordon E. Kaye, R.D. 1, Howland Road,
Garrison, N.Y. 10524

Filed Sept. 4, 1973, Ser. No. 393,764

Term of patent 14 years

Int. Cl. D13—02

U.S. Cl. D26—6

FIG. 1

FIG. 3

FIG. 2

FIG. 4

FIG. 5

FIG. 7

FIG. 6

FIG. 8

FIG. 1 is a view from the terminal side of an electric battery showing my new design.

FIG. 2 is a top plan view thereof, the bottom being the same.

FIG. 3 is a side view as taken from the left of FIG. 2.

FIG. 4 is a side view as taken from right of FIG. 2.

FIG. 5 is a side view as taken from the bottom of FIG. 2.

FIG. 6 is an interior view of the bottom half of the battery, the top being omitted for purposes of disclosure.

FIG. 7 is a side view as taken from the top of FIG. 6.

FIG. 8 is a cross-sectional view taken in line 8-8 of FIG. 6.

I claim:

The ornamental design for an electric battery, as shown and described.
